UNITED STATES PATENT OFFICE.

JOHN HAVLICEK AND JAMES B. SCULLANE, OF SPRINGFIELD, MASSACHUSETTS.

GUN-CLEANER.

1,156,683.

Specification of Letters Patent.

Patented Oct. 12, 1915.

Application filed March 1, 1915. Serial No. 11,390.

To all whom it may concern:

Be it known that we, JOHN HAVLICEK and JAMES B. SCULLANE, citizens of the United States, and residents of Springfield, 5 in the county of Hampden and State of Massachusetts, have invented certain new and useful Improvements in Gun-Cleaners, of which the following is a specification.

Our present invention relates to gun 10 cleaners, and more particularly to all-metal attachments for effectively cleaning the barrels of rifles and guns of various bores, our object being to provide a simple, strong, and durable implement, attachable either to a 15 cord or rod for passing the same through the barrel of the gun, and provided with all metal cleaning or scouring elements and with means for holding and carrying a fabric whereby the barrel of the gun may be 20 wiped following the cleaning members.

The objects, together with their resulting 25 advantages, of our present invention, will be better understood from the following description in which reference is made to the accompanying drawing, forming a part of this specification, and in which—

Figure 1 is an elevation illustrating the body strands and the cleaning coils of our 30 improved gun cleaner, previous to the formation of the completed cleaner by twisting the said body strands, Fig. 2 is a transverse enlarged section through one of the body strands, taken substantially on line 2—2 of Fig. 1, Fig. 3 is an elevation of the 35 complete cleaner, illustrating the same attached to a cord or wire, and provided with a cleaning fabric, Fig. 4 is a side elevation of a portion of the complete cleaner enlarged, Fig. 5 is a transverse section taken 40 therethrough substantially on line 5—5 of Fig. 4, Fig. 6 is a longitudinal section of a portion of the cleaner illustrating a slightly modified form, and Fig. 7 is a transverse section taken substantially on line 7—7 of 45 Fig. 6.

Referring now to these figures, our improved gun cleaner consists of a body portion A as best seen in the complete form of the cleaner in Fig. 3, together with end 50 loops B and C, the former of which is provided for the reception of a wiper or fabric D, and the latter of which provides either for the attachment of the body A to a cord or wire E, as shown in this figure, or to a 55 cylindrical attaching member F as shown in Figs. 6 and 7, through slots f of which the

said loop C is passed, the said attaching member F having a reduced threaded extension f' by which it may be secured to a carrying rod and the like G.

The body A is, in either of the forms mentioned, constructed of a pair of body strands A', as best seen in Figs. 1, 4, and 5, each of these body strands, which are integrally united at one end, being provided 60 with a surrounding coil H of relatively small gage wire, the convolutions of which are substantially greater in diameter than the body strands A' as will be clearly seen by reference to Figs. 2 and 5. The body 65 strands A' are twisted around one another in their length, their continuations being twisted as best seen in Fig. 3 to form the end loops B and C. Throughout the body therefore the cleaning coils H are securely 70 held in the manner shown in Fig. 5, by the engagement of the strands A' in their 75 twisted relation.

By reference to Figs. 2, 4, and 5 in particular, it will be seen that the like cleaning 80 coils H, have each of their convolutions in polygonal form, that is, provided with a plurality of angular portions, in order that when held by the twisted body strands A' in the finished cleaner, the cleaning coils present a series of relatively sharp extensions h 85 as best seen by reference to Fig. 5, following helical lines throughout the length of the body A of the cleaner.

The engagement of the body strands A' 90 in their twisted relation, effectively and rigidly hold the cleaning coils H against displacement, but at the same time, these coils being of greater diameter than that of the body strands A', are permitted to give to a 95 certain extent in order that when within a bore of slightly smaller diameter, the tendency of the convolutions of the coils H will be to expand, thus forcing their relatively sharp projections h into close contact with 100 every portion of the wall of the bore.

In this manner, the gun cleaner proposed by our invention, being all metal in its construction, is very strong and durable, and presenting as it does a multitude of relatively sharp projections, is very effective for the purpose of removing rust and lead from the gun bore. Furthermore, the gun cleaner so constructed may carry with it a cleaning fabric or wiper such as shown in Fig. 3, at 105 D, in order to effectively wipe the gun bore 110 after cleaning.

We claim:—

1. A gun cleaner having a body portion and end loops, said body portion consisting of twisted strands, and a cleaning coil surrounding each of the said body strands and held by the engagement of the strands in their twisted relation.
2. A gun cleaner having a body portion consisting of twisted strands, and a cleaning coil surrounding each of the said strands and held in place by the engagement of the strands in their twisted relation.
3. A gun cleaner having a body portion and end loops, said body portion consisting of twisted strands, and a cleaning coil surrounding each of said body strands and held by the engagement of the strands in their twisted relation, the ends of the body strands being bent to form the said end loops.
4. A gun cleaner having a body portion consisting of twisted strands, and a cleaning coil surrounding each of the said strands and held by the engagement of the strands in their twisted relation, each of the said cleaning coils having convolutions greater in diameter than the diameter of the said body strands, and each of the said convolutions of the coils being of polygonal shape.
5. A gun cleaner having a body portion consisting of twisted strands, and a cleaning coil surrounding each of the said strands and held by the engagement of the strands in their twisted relation, each of the said cleaning coils having convolutions greater in diameter than the diameter of the said body strands, and each of the said convolutions of the coils being of polygonal shape.
6. A gun cleaner having a body portion consisting of twisted strands, and a cleaning coil surrounding each of the said strands and held by the engagement of the strands in their twisted relation, each of the said cleaning coils having convolutions greater in diameter than the diameter of the said body strands, and each of said convolutions of said coils having angular portions forming outwardly projecting apices.
